Term of patent 14 years

(Cl. D86—10)

FIG. 1 is a front elevational view of a mirror showing my new design.

FIG. 2 is a top plan view thereof.

FIG. 3 is a fragmentary side elevational view of the support between the pedestal and mirror support arms shown in FIG. 1.

The rear of the mirror is substantially similar to the front shown in FIG. 1.

This is a division of my copending application Serial No. D. 66,897, filed on Sept. 28, 1961.

I claim:

The ornamental design for a mirror, as shown and described.
